UNITED STATES PATENT OFFICE.

FRANK PARDEE, OF HAZLETON, PENNSYLVANIA, ASSIGNOR TO ANTHRACITE SEPARATOR COMPANY, OF HAZLETON, PENNSYLVANIA, A CORPORATION OF PENNSYLVANIA.

SPIRAL SEPARATOR.

Application filed April 1, 1925. Serial No. 19,755.

The invention relates to spiral separators and particularly to an improved type in which I utilize jets of air to augment the action of the centrifugal force in effecting a more complete separation than that obtainable by the ordinary gravity spiral.

In a prior patent granted to me, I have disclosed means for discharging jets of air or other fluid from the bottom of a runway so as to augment the separating action in a spiral separator. One of the advantages of the construction disclosed is that an extremely efficient separation can be secured with a runway much lower than those depending solely on the action of gravity and centrifugal force.

The present invention relates to the separator operating on the same broad principle as that of my former patent and aims to provide a structure embodying certain detailed improvements. In my former patent the runway is substantially flat and no means are shown for inclosing the same.

In the present invention the runway is in the form of a spiral pipe which is entirely enclosed so that there is no escape of dust or small particles of coal discharged into the atmosphere throughout the length of the runway by the influence of the blast. Other advantageous features will be apparent from the following description and the invention will be pointed out with particularity in the appended claims.

An embodiment of the invention is illustrated in the accompanying drawings in which Fig. 1 is an elevation with portions broken away for the purpose of better illustration;

Fig. 2 is a transverse section on line 2—2 of Fig. 1;

Fig. 3 is a longitudinal section of a portion of the spiral runway pipe and its enclosure.

Referring in detail to the drawings, 10 represents a series of uprights which may be of angle iron or other suitable material secured to a suitable base, not shown, and connected by any convenient type of structural bracing. The uprights carry brackets 12 which support a substantially spiral or helical shaped casing 14. This casing is supplied near its upper end with a suitable fluid under pressure through a pipe 16 which is connected with a pump or centrifugal fan 18. Lo-

cated within the casing 14 is a runway pipe 20 of spiral form which is of substantially the same pitch as the casing 14. The runway pipe is provided with a multiplicity of obliquely inclined ports 22 which communicate with the interior of the casing 20 and permits fluid therefrom to be discharged in such a direction that it influences the travel of the materials flowing on the separator and augments separating action.

The runway pipe 20 is adjustably supported within the casing 14 by a plurality of radially extending bolts 24 which are threaded through suitable openings in the wall of the casing. It will be understood that by manipulating these bolts the relative position between the runway pipe and the casing can be varied so that they can be either concentric or eccentric as desired. The upper end of the casing is closed by a cap 26 which is secured to a flanged ring 28 carried by the casing, the securing bolts 30 passing through clearance holes 32 in the cap so as to permit the relative adjustment between the pipe and the casing referred to. At the lower end the casing is provided with a similar cap or closure 32 secured by bolts 34 which pass through clearance holes 36.

The lower end of the separator pipe 20 projects beyond the cover plate 32 and is cut away as shown to permit the coal to discharge over the edge 38 and the slate to discharge over the edge 40. The edge 38 will usually be at a slightly higher elevation than the edge 40. The coal or lighter material handled, because of the action of centrifugal force, and the action of the fluid jets discharged through the oblique ports 22, will flow in an outer path along the separator pipe and will have a tendency to climb the wall thereof. Naturally as this stream of coal reaches the lower end of the pipe, the coal is in the outer zone and it will readily climb over the edge 38 and be discharged as indicated by the arrows 42 into a coal chute 44 leading to a suitable bin, not shown. The slate and other refuse due to greater friction and weight will be discharged inwardly as indicated by the arrows 46, such material falling over the edge 40 into the chute 48 which directs this material to the suitable bin. The intermediate material consisting of a mixture of coal and slate which fails to go over either edge 38 or 40

is discharged into a chute 49 leading to a bin or in some cases to another separator.

The upper end of the separator pipe 5 shown projects beyond the cover 26 of the casing and a suitable feed chute 50 is indicated for directing the mixed materials to the intake end of the separator pipe.

Though I have described with great particularity the specific embodiment of the invention herein illustrated, it is not to be construed that I am limited thereto as various modifications in design and arrangement may be made by those skilled in the art without departing from the invention as defined in the appended claims.

What I claim is:

1. A separator comprising a pipe of spiral form having its inlet at a higher elevation than its outlet so that the material to be separated travels downward by gravity and means for discharging jets of fluid through the walls of said pipe to assist in the separating action.
2. A separator comprising an air upright pipe of spiral form through which the material to be separated travels downward by gravity, a casing surrounding said pipe and means for supplying a fluid to said casing, said pipe having a multiplicity of ports formed in the wall thereof.
3. A separator comprising a pair of spiral pipes nested one within the other and whose convolutions are inclined to a horizontal plane, the inner pipe having a series of ports therein and the outer pipe being connected with a source of fluid pressure.
4. A separator comprising a spiral pipe through which the material to be separated travels, a casing surrounding said pipe, means for supplying a fluid to said casing, said pipe having a series of ports therein through which fluid is admitted to assist in the separation of materials travelling through it, the pipe being adapted to re-

ceive the mixed materials at its upper end 45 and having its lower end cut away and shaped so that one class of material is discharged outward and another class is discharged inward.

5. A separator comprising a pipe of spiral 50 form through which the material to be separated travels, means for discharging jets of fluid through the walls of the pipe to assist the separating action, said pipe being adapted to receive the mixed materials at 55 its upper end and having its lower end formed to permit one class of material to be discharged over the outer edge of the pipe and another class of material to be discharged over the inner edge. 60

6. A separator comprising a pipe of spiral form through which the material to be separated travels, a plurality of ports formed therein, a casing surrounding the pipe for the greater part of its length, said pipe 65 having a cut away discharge portion extending beyond the casing and means for supplying fluid under pressure to said casing.

7. A separator comprising a pipe of spiral 70 form through which the material to be separated travels, a plurality of ports formed therein, a casing surrounding the pipe for the greater part of its length and means for changing the position of the pipe with respect to the casing. 75

8. A spiral separator including a pipe through which the material travels, a casing of substantially circular cross-section surrounding the latter and adjustable supporting means whereby the pipe can be supported either concentric with or eccentric to the casing, said pipe having ports therein providing communication with the interior of said casing. 80 85

In witness whereof, I have hereunto signed my name.

FRANK PARDEE.
